UNITED STATES PATENT OFFICE.

PAUL SCHMIDT AND ADOLPHE DESGRAZ, OF HANOVER, GERMANY.

GAS-PRODUCER.

No. 903,112.

Specification of Letters Patent.

Patented Nov. 3, 1908.

Application filed July 16, 1907. Serial No. 384,126.

To all whom it may concern:

Be it known that we, PAUL SCHMIDT, a subject of the Emperor of Germany, and ADOLPHE DESGRAZ, a citizen of Switzerland, 5 residing at Hanover, Germany, have invented certain Improvements in Apparatus for Feeding Coal to Gas-Producers, of which the following is a specification.

The apparatus to which this invention relates has for its object, in gas producers supplied with coal by mechanical means, whether arranged as single apparatus or in series, to enable the supply of coal during the operation thereof to be adjusted in a 15 very simple manner.

The accompanying drawing shows one constructional form of apparatus in accordance with this invention, together with the upper part of a gas producer in section.

20 Coal is supplied to the feed receptacle *a* from above through an aperture *b* and thereupon falls first through the lower opening *c* which is of cylindrical form and arranged concentrically with the gas producer, and 25 then upon the distributor *d* which is rotatably arranged in the well known manner at a certain distance below the opening *c*. The distributor *d* may be attached by means of several arms *e* to a rotatable casing *g*, 30 the lower part of which is immersed in a circular water trough *h* and the upper part of which is constructed to form a trough *i* for the reception of water. To this trough into which there projects a stationary flange 35 *w* which forms a seal, there is attached an angular ring *k* the lower part of which runs on rollers *l* and the upper part of which is provided with teeth with which there engages the ratchet mechanism *f*. The rollers 40 *l* are connected with supports *m* which carry the upper portion of the feed apparatus.

In the lower cylindrical opening *c* of the feed apparatus *a* there is suspended from a spindle *q* to be freely movable by means of 45 the arms *o* a hollow cylindrical body *n*, which can at any time be easily raised or lowered by means of the hand-wheel *p*, the

space between the lower edge of the cylindrical body *n* and the upper round disk of the distributor *d* being thus capable of being increased or diminished as desired. The cylinder *n* may, however, be raised or lowered from the outside by any other suitable means, such for instance, as lever mechanism. As all the coal must pass through the inner opening of the cylinder *n* it is clear that assuring the distributor *d* moves at a definite and constant speed, the amount of coal passing into the gas producer will depend on the size of the space between the distributor *d* and the cylinder *n*; and that as in apparatus constructed in accordance with the present invention the size of the space may be easily and quickly changed at any time without interfering with the operation of the apparatus the object of the invention, that is to say, the power of varying easily and quickly the amount of coal supplied to a gas producer while the feed apparatus is in operation and without changing the rate of rotation of the distributor, is achieved.

Having thus described our invention, what we claim and desire to secure by Letters-Patent is:

75 The combination, with a generator, and a hopper rigidly supported above the generator, of a rotary distributor mounted in the upper end of the generator directly below the discharge opening of the hopper and 80 having water-seal connections with both the generator and the hopper, means for rotating said distributor, and a cut-off mounted in the discharge opening of the hopper and 85 adjustable therein to and from the distributor.

In testimony whereof we have hereunto set our hands in presence of two subscribing witnesses.

PAUL SCHMIDT.
ADOLPHE DESGRAZ.
